UNITED STATES PATENT OFFICE.

ROSIE THAMM, OF BERKELEY, CALIFORNIA.

DESIGN FOR A NAPKIN-HOLDER.

48,357.

Specification for Design.

Patented Dec. 28, 1915.

Application filed July 19, 1915. Serial No. 40,783. Term of patent 3½ years.

To all whom it may concern:

Be it known that I, ROSIE THAMM, citizen of Chile, residing at Berkeley, in the county of Alameda and State of California, have invented a new, original, and ornamental Design for Napkin-Holders, of which the following is a specification, reference being had to the accompanying drawing, forming part thereof.

The figure is a view in perspective of the napkin holder, showing my new design.

I claim:

The ornamental design for a napkin holder, as shown.

In testimony whereof I affix my signature.

ROSIE THAMM.
